UNITED STATES PATENT OFFICE.

CHARLES A. BENNETT, OF TAUNTON, MASSACHUSETTS, ASSIGNOR TO REED & BARTON CORPORATION, OF TAUNTON, MASSACHUSETTS, A CORPORATION OF MASSACHUSETTS.

DESIGN FOR A HANDLE FOR SPOONS, FORKS, OR SIMILAR ARTICLES.

SPECIFICATION forming part of Design No. 35,408, dated December 10, 1901.

Application filed October 25, 1901. Serial No. 79,964. Term of patent 14 years.

To all whom it may concern:

Be it known that I, CHARLES A. BENNETT, a citizen of the United States, and a resident of Taunton, in the county of Bristol and State 5 of Massachusetts, have invented and produced a new and original Design for the Handles of Spoons, Forks, or Similar Articles, of which the following is a specification, reference being had to the accompanying drawings, which 10 form a part hereof.

In the drawings, Figure 1 represents a plan view of a spoon or fork handle exhibiting my new and original design, and Fig. 2 is a side view thereof.

15 From the narrow portion or shank of the handle, at about the point marked *a*, there is developed in bas-relief the form of a bud sufficiently conventionalized to adapt it to the general shape of the article to which it is applied. This bud *b*, as shown in the drawings, 20 is of the form and character of the fleur-de-lis. Next above the bud ornamentation at *b* the design develops a second flower figure, also in bas-relief. This flower figure, as shown

in the drawings at *c*, is of the form and character of the poppy blossom. Next above the blossom ornamentation at *c* the design develops another flower figure in bas-relief. This flower figure, as shown at *d*, is of the form and character of an orchid. Lastly, at 30 the end of the handle the design develops a fourth figure in bas-relief. This figure, as shown at *e*, is of the form and character of a peony blossom. The petals of the flowers and the foliage ornamentations which accompany 35 them and assist in the composition conform to the general outline of the handle.

What I claim, and desire to secure by Letters Patent, is—

The design for a handle, for spoons, forks, 40 or similar articles, substantially as herein shown and described.

Signed by me at Taunton, this 23d day of October, 1901.

CHARLES A. BENNETT.
